UNITED STATES PATENT OFFICE.

MAX HERSKOVITZ, OF CHICAGO, ILLINOIS, ASSIGNOR TO PEERLESS LIGHT COMPANY, OF CHICAGO, ILLINOIS, A CORPORATION OF MAINE.

ELECTRIC-SOCKET-SUPPORTING STRUCTURE.

Application filed February 21, 1921. Serial No. 446,565.

To all whom it may concern:

Be it known that I, MAX HERSKOVITZ, a citizen of the United States, residing at Chicago, in the county of Cook and State of Illinois, have invented a new and useful Improvement in Electric-Socket-Supporting Structures, of which the following is a specification.

My invention relates more particularly, though not exclusively, to electric-socket-supporting structures of the type which are supported from a base, as is common with table or floor lamps; and one of my objects is to provide for the supporting of the electric-bulb-receiving sockets in a manner to permit the sockets to be adjusted into different positions relative to the part which supports them, preferably to cause the bulbs carried thereby to extend downwardly or in either direction in a substantially horizontal plane. Other objects are to provide a novel, simple, substantial and inexpensive construction adapted for manipulation as stated; to provide a new and improved form of combined housing for the electric wires, and support for a socket or sockets, which shall be strong and durable and may be used in a variety of locations and used with either of its wire-receiving tubular portions uppermost; and other objects as will be manifest from the following description.

Referring to the accompanying drawings:

Figure 1 is a view in elevation of the upper end of a socket-supporting structure provided with a plurality of bulb-receiving sockets, and embodying my invention, showing the sockets in a position in which the bulbs supported therein and shown by dotted lines, assume a depending position. Figure 2 is a similar view showing the bulb-receiving sockets extending in substantially horizontal position but in opposite directions. Figure 3 is a plan section of the construction shown in Fig. 2, with the sockets positioned as represented therein, the section being taken at the line 3 on Fig. 2 and viewed in the direction of the arrow. Figure 4 is an enlarged face view of a portion of the structure shown in Fig. 1, with the bulb-receiving sockets shown partly broken away, the cap-plate at this side of the structure being removed to show interior details. Figure 5 is an inner face view of the cap-plate above referred to. Figure 6 is an enlarged section taken at the line 6-6 on Fig.

1 and viewed in the direction of the arrows. Figure 7 is a vertical section taken at the line 7 on Fig. 1 and viewed in the direction of the arrow. Figure 8 is a plan view of the enlarged, generally spherical, portion of the device of Fig. 1 from which the sockets extend, showing the parts forming this substantially spherical portion, in spaced, but related, positions, the portion of the structure immediately above the said spherical portion being shown in section; and Figure 9, an enlarged broken section taken at the line 9 on Fig. 4 and viewed in the direction of the arrow.

In the particular arrangement shown, wherein I have illustrated my invention as applied to an electric-socket-supporting structure of the type involving a base at which the structure is adapted to be supported, as for example, on a table or a floor, with a standard rising therefrom and supporting adjacent its upper end, the bulb-receiving sockets, the upright, or standard, portion, which is shown as formed of a tube, is represented at 10, this tube not only serving as a support but also serving to enclose the electric-current-conducting wires which lead to the bulb-receiving sockets hereinafter referred to. The upper end of the tubular upright 10 is secured to a housing member 11, as by screwing the member 10 into the hollow depending boss portion 12 of the housing 11. This boss member 12 is provided as a part of a ring-shaped member 13, which is formed, preferably integrally, with an upwardly-extending boss 14 preferably in vertical alignment with the boss 12. The housing portion 11 also comprises cap-plates 15 and 16 of general dish shape as shown, preferably of semi-spherical form as shown, which are adapted to be assembled with the ring-shaped member 13 at the opposite ends of the opening therethrough, in a manner hereinafter described, to complete the housing and cause the housing to be of substantially spherical form as shown. In the particular construction shown the manner of attaching the cap plates to the stationary portion 13 of the housing involves the provision at the opposite ends of the member 13, of the flanges 17 which are in the form of annuli, except for the cut-away portions as represented at 18, the circumferences of these flanges being undercut as represented at 19. The cap-plates 110

15 and 16 are adapted to be telescoped with the flanges 17 and be interlocked with relation to the latter, as for example by the provision, on each of these cap-plates, of 5 diametrically-opposed, inwardly-extending lugs 20 which may be formed by bending inwardly the metal of which these cap portions are formed, the length of these lugs being slightly less than the length of the 10 voids 18. The parts just described are so proportioned that in assembling the cap-plates 15 and 16 with the member 13, the lugs 20 may be caused to extend into the voids 18, and then by rotating the cap-plates, 15 these lugs will enter the undercut portions 19 and thereby interlock the cap-plates with the stationary member 13 as shown, these plates being readily removable from the member 13 by rotating them to a position in 20 which the lugs 20 register with the voids 18.

The bulb-receiving sockets of the structure are represented at 21, and may be of any desirable construction, as for example those now commonly in use, thus rendering unnecessary 25 the description of these sockets. In the particular construction shown two of these sockets are employed located at opposite sides of the housing member 11, and so supported that they may be independently 30 swung on this housing member into different positions in a vertical plane, as for example to depend from the housing member, or extend horizontally therefrom in either direction, the particular construction of 35 socket shown being of the pull-chain type, the chains of which are shown at 22, the bulbs fitted into the sockets 21 being represented by dotted lines at 21^a in Fig. 1, where- 40 in the parts are shown as adjusted to a position in which the bulbs are in depending position.

Each of the sockets 21 is supported from the housing by a clamping ring represented at 23, these rings surrounding the sockets 45 and being held thereto, as by the screws 24 passing through the rings and screwing into the sockets. The ends of the members forming the rings, and represented at 25, extend through diametrically-opposed openings 26 in the ring member 13, at which portions this member is of enlarged cross-section as shown at 27. The extremities of the 50 portions 25 are bent in opposite directions away from each other to provide the out-turned ends 28, between which and the inner faces of the enlarged portions 27, rings 29, loosely surrounding the ends of the members 25, extend. It will thus be noted that 55 each of the socket members 21 is free to be rotated upon the housing 11 into different angular positions hereinbefore described. The rings 29 are of such size that they do 60 not snugly embrace the portions 25, but a slight clearance is provided therebetween, 65 and to effect the desired frictional engage-

ment of the portions 25 with the walls of the openings 26 through which they extend, I provide any suitable means, as for example the screw devices represented at 30 which extend through unthreaded openings 31 in 70 the rings 29, engaging at their threads with the threads of openings in the adjacent ones of the end portions 25, and extending at their inner extremities into engagement with the other end portions 25. Thus by tightening the screws 30 the end portions 25 may be caused to be spread apart, against their tendency to draw together, and thereby present the desired frictional engagement between them and the walls of the openings 26 75 through which they extend, whereby the sockets 21, with the bulbs therein, while being free to be moved to different positions on the housing 11, will be caused to remain in such adjusted positions. 80

The sockets may be connected with the current-conducting wires in any desirable way, such connecting wires being represented at 32 and located within the housing 11, these wires extending through the rings 29 90 and the space between the arms 25 and the openings 26 and thence into the interiors of the sockets 21 through openings (not shown) in the side walls of the latter. 95

It is desirable that some means be provided for preventing undue rotation of the socket members 21 on the housing 11 to prevent the straining, or breaking, of the electrical connections and involving the wires 32, the means shown in the particular construction illustrated, involving the provision on the ring member 13, at opposite sides thereof, of a pair of stops 33 presenting the shoulders 34 which extend into the path of movement of the outer ends 35 of the screws in the rotating of the sockets on the housing 11, these stops being so located that the sockets will be capable of rotation throughout substantially 180°, though this may be varied as desired. The uppermost ones of 100 the stops 33 of each set thereof limits the upward swing of the sockets in one direction, and the lower ones of the stops 33 limits the upward swing of these sockets in the opposite direction, the screw-ends 35 extending 105 substantially midway between the stops of each pair thereof when the sockets are in depending position. 110

It will be readily understood from the foregoing that the structure may be readily 115 wired, particularly because of the provision of two cap-plates, one at each side of the housing.

The device as shown also provides for the securing to the upright portion of the 120 structure, of a lamp shade, the same being securable at different elevations. This is effected in the particular structure shown by the provision of a threaded rod 37 which screws into the upper boss 14 and carries 125

two disks 38 and 39 threaded thereon, the upper end of the rod 37 being shown as provided with an ornamental section 40. By virtue of the adaptability of the rod 37 to adjustment up and down on the housing 11 and the adaptability of the disks 38 and 39 to independent adjustment on the rod 37 the structure is adapted to support shades at different elevations relative to the housing 11 and in a manner to present an ornamental appearance. It will be noted that the wires in the housing may be pushed back to permit the rod 37 to screw into the housing to the desired distance in the adjustment of this rod.

What I claim as new, and desire to secure by Letters Patent, is:

1. In an electric-socket-supporting structure, the combination of a hollow supporting member presenting a chamber and containing an opening in its wall, an electric-bulb-receiving socket located exteriorly of said supporting member, and means engaging said socket and engaging said supporting member adjacent said opening and affording a rotatable mounting for said socket on said supporting member, said means comprising a band member surrounding said socket and engaging said supporting member.

2. In an electric-socket-supporting structure, the combination of a hollow supporting member presenting a chamber and containing an opening in its wall, an electric-bulb-receiving socket located exteriorly of said supporting member, and means engaging said socket and extending through said opening and affording a rotatable mounting for said socket on said supporting member, said means comprising a band member surrounding said socket, with the ends of said band member extending through said opening and a member interlocking with the inner portions of said ends for holding said socket and band member in operative relation to said supporting member.

3. In an electric-socket-supporting structure, the combination of a supporting member containing an opening, an electric-bulb-receiving socket, and means rotatably mounting said socket on said member comprising a socket-supporting device engaging the socket and presenting spaced apart portions which extend through said opening, the extremities of said portions presenting outwardly directed shoulders, and a member surrounding said end portions and confined between said shoulders and the inner surface of said supporting member.

4. In an electric-socket-supporting structure, the combination of a supporting member, said supporting member containing an opening, an electric-bulb-receiving socket, and means rotatably mounting said socket on said member comprising a socket-sup-

porting device engaging the socket and presenting spaced-apart portions which extend through said opening, the extremities of said portions presenting outwardly directed shoulders, and a member surrounding said end portions and confined between said shoulder and the inner surface of said supporting member, and an adjusting device engaging said end portions and adapted to vary the distance between the latter.

5. In an electric-socket-supporting structure, the combination of a supporting member, said supporting member containing an opening, an electric-bulb-receiving socket, and means rotatably mounting said socket on said member comprising a socket-supporting device engaging the socket and presenting spaced-apart portions which extend through said opening, the extremities of said portions presenting shoulders, a member loosely surrounding said end portions and located between said shoulders and the inner surface of said supporting member, and means for relatively adjusting said portions to vary the degree of friction exerted between them and the wall of said opening and comprising a screw threaded in one of said end portions and bearing against the other thereof.

6. In an electric-socket-supporting structure, the combination of a supporting member, said supporting member containing an opening, an electric-bulb-receiving socket, and means rotatably mounting said socket on said member comprising a socket-supporting device engaging the socket and presenting spaced-apart portions which extend through said opening, the extremities of said portions presenting shoulders, a ring loosely surrounding said end portions and located between said shoulders and the inner surface of said supporting member, and means for relatively adjusting said portion to vary the degree of friction exerted between them and the wall of said opening and comprising a screw extending through said ring and threaded in one of said end portions and engaging the other of said end portions.

7. In an electric-socket-supporting structure, the combination of a housing formed of separable sections, a supporting standard and a shade-attaching member rigidly mounted on the upper and lower portions of one of said sections, and a socket carried by said last-referred-to section at a side thereof, the said section of said housing to which said standard and shade-supporting member are attached presenting a lateral opening over which the other section of said housing extends, said last-referred-to section being removable and replaceable without affecting the position of the others of said parts.

MAX HERSKOVITZ.
